6 Claims. (Cl. 153—2)

This invention relates to an improved stretching machine for flattening metal strip.

In the production of strip metal, particularly in the light alloys, it is often necessary to ensure absolute flatness, and since this cannot be obtained except by stretching, some form of stretching machine is required.

In the case of sheets, that is short strips, the stretching operation has long been accepted practice and there are various forms of sheet stretcher usually consisting of one gripper head moved backwards and forwards to fixed positions by means of screws and the other gripper head actuated by a hydraulic cylinder.

It is inconvenient to handle strips in the flat condition and therefore it is usual to arrange for a strip to be coiled at the end of each operation, that is, rolling, pickling, washing, annealing, slitting and edge trimming, etc. This means that to stretch strip it is necessary to uncoil this and after stretching to re-coil it. It is known that this work is carried out in some works at the moment by uncoiling the strip as one operation, and then transferring the strip to the stretcher after which it is passed to a coiler. Such a plant occupies a considerable amount of space and there is grave risk of mechanical damage to the strip owing to the excessive amount of handling.

The object of the present invention is to obviate excessive handling and to reduce the space required for effecting the operation.

The machine according to the invention, which receives as a coil the metal strip to be flattened, comprises a gripper head and uncoiling means working together so that as uncoiling of the coil of strip proceeds the uncoiling means and one gripper with the tail end of the strip in its grip are moved further apart, with the uncoiled strip held out between them, until the uncoiling has finished, whereupon the other end of the strip having been gripped by the other gripper, the two grippers co-operate to stretch the uncoiled strip and effect the desired flattening.

Levelling means are provided through which the uncoiling strip passes as it travels from the coil to the gripper which is gripping the tail end of the strip. This gripper is preferably arranged so that it is caused to travel longitudinally along the bed of the machine synchronously with the uncoiling of the strip. Reversal of the travel of the gripper is effected as soon as the last portion of the uncoiled strip has been levelled and this causes the uncoiled strip to move so as to bring the free end of the strip into the other gripper. This other gripper is preferably the one which is

caused to move to stretch the strip, the other gripper being anchored at an appropriate point in its path of travel.

After the strip has been stretched the machine according to the invention provides for its being recoiled. In the case of heavier gauge material means will be provided for bending the strip to cause it to be re-formed into a coil. With thinner gauge material a drum type of coiler may be used. The travelling gripper will be driven so that it returns with the tail end of the strip and flattened strip in its grip with a movement synchronised with the recoiler.

The following is a description of the preferred construction of the machine according to the invention.

The invention is illustrated in the accompanying drawings in which Figure 1 is a side elevation of one end portion of a complete machine, and Figure 1^a is a side elevation of the other end portion of the machine, it being intended that Figures 1 and 1^a be read as though the left hand end of Figure 1^a were joined to the right hand end of Figure 1. Figure 2 is a top plan of the end portion shown in Figure 1, and Figure 2^a is a top plan of the end portion shown in Figure 1^a, it being understood that Figures 2 and 2^a are to be read as though the left end of Figure 2^a were joined to the right end of Figure 2. Figures 3-8 are detail views to a larger scale of the various component parts of the machine, Figure 3 being at the left hand side a sectional elevation on the line III—III Figure 4 and on the right hand side a sectional elevation, Figure 4 being on the left hand side a sectional elevation on the line IV—IV Figure 3 and on the right hand side an end elevation, Figure 5 being a sectional elevation, Figure 6 being a side elevation of the gripper head, and Figures 7 and 8 respectively plan and side elevations of mechanism provided for supporting the strip.

The machine comprises a main bed 1, preferably of fabricated construction, on which is mounted a device indicated generally at 2 which may be called an uncoiler-leveller-recoiler. There may also be mounted a conventional form of drum type uncoiler-coiler for use when thin gauge material is dealt with this being indicated generally at 3.

On the bed 1 to one side of the uncoiler-leveller-recoiler 2 there is mounted the travelling gripper head 4, whilst on the other side there is the gripper head 5 associated with hydraulic means 6 for causing it to move to that extent which is neces-

sary to stretch the strip to effect the flattening which is required.

The uncoiler-leveller-recoiler comprises two carrier rolls 7 for the coiled strip and a number of levelling rolls 8 the various rolls being driven by an electric motor 9 through gearing 10 and if necessary, a reducing worm gear 11, the use of which depends on the speed of operation which is decided upon. The various gear wheels 10 terminate in universal connections 12 coupled by rods 13 having universal connections 14 to one of the ends of the various rolls to be driven.

The levelling rolls 8 are divided into an upper bank A and a lower bank B. The two carrier rolls 7 and the upper levelling rolls A are mounted at their ends on spaced bearing blocks 15 and provided with robust guides 16 so as to permit vertical movement of the blocks 15 and their rollers. The bearing blocks are counter-balanced by means, for example, of springs as shown at 17 or hydraulic cylinders, with sufficient stroke to leave the upper levelling rolls A well clear of the strip when the latter is being stretched between the two gripper heads 4 and 5.

The downward movement of the bearing blocks 15 is suitably effected by means of wedges 18 actuated by a ram and cylinder arrangement 19 operated pneumatically or by any other fluid pressure medium. To couple the ram to the wedges 18, the ram is provided with a rod 20 having on it a swivel block 21 engaged by a fork 22 on one arm of a lever 22' pivoted at 23 and the other arm of which is pivoted at 24 to a link 25 pivoted at 26 to the wedge 18 at one end of the rollers and this wedge is itself connected to the other wedge 18 by a coupling rod 27; thus when the ram 19 is caused to move, the lever 22' is caused to rock and both wedges are move equally. The stroke of this ram 19 may be regulated by means of an adjustable stop so as to enable correct levelling of various gauges of material to be obtained. This is effected by extending the rod 27 and securing to it a sleeve 28 having a flange 29 which in the limiting position engages a flange 30 on a collar 31 which is screw threaded to engage in a fixed threaded socket 32, the collar 31 having a hand-wheel 33 and a lock wheel 34 for the purpose of adjusting the position of the flange 30 and hence of the limiting position which is indicated on a scale 35.

One of the lower levelling rolls B (this being indicated at 8') is provided with an independent adjustment so that it will serve as a bending roll for the recoiling of the strip. The adjustment may be effected by a worm and screw gear or by a screw and bevel gear or by a fluid-pressure cylinder having an adjustable stroke. For this purpose the roller 8' is independently mounted in blocks 36 fast with screwed rods 37 engaged by nuts 38 formed with a worm wheel 39 engaged by worms on a transverse operating spindle 40 so that when this spindle is rotated, the blocks 36 are adjusted vertically simultaneously.

Between the carrier rolls 7 there may be mounted a floor plate 41 having a number of idle rolls 42 and adjustable side guards 43 may be provided to centre the coil, these guards being adjusted by means of locking pins or by screws 44, or by rack and pinion as preferred.

The drum type uncoiler-coiler 3 may be of conventional design provided with simple means of expansion and collapse and it is preferably overhung from a rigid bearing 45 and is coupled to an electric motor 46 by spur or worm gearing.

Declutching means are provided to enable the

coiler to freewheel whilst uncoiling whilst the motor 46 is preferably of the variable speed type so as to permit a constant speed of coiling to be obtained in synchronism with the return travel of the travelling gripper head.

Where the radial thickness of a complete coil is not large relative to the diameter of the drum, a slipping clutch may be interposed in the drive so as to permit the drum to slip to compensate for the growth of the coil so as to enable the peripheral speed of the strip on the drum to synchronise with that of the levelling unit and the winch.

The gripper heads 4, 5 may be designed according to any of the known methods of gripping, though it is preferred to have gripper jaws of the parallel motion type.

The gripper head 5 which moves to effect the stretching is provided with ballbearing rollers running on the bed 1 and is coupled by means of pull rods 47 to a crosshead 48 fast with the main ram 49 which runs in the hydraulic cylinder 6. A ram 50 for returning the gripper head 5 after the stretching operation is mounted in a cylinder which is ambushed in the main hydraulic cylinder and the hollow bore of the main ram 49.

The crosshead 48 which is coupled with the main ram 49 has a roller support 51 running on a track 52 formed as an extension of the bed 1 of the machine.

The return ram 50 may be under constant pressure and the main ram 49 operated by a single acting hydraulic valve, or alternatively both the return ram and the main ram may be operated by means of a double acting hydraulic valve.

The travelling gripper head 4 is mounted on ball or roller bearing rollers 53 and has an extension 54 formed to carry the fulcrum pin 55 on hooks 56 which are designed to anchor the travelling gripper head 4 during the stretching operation. The hooks are balanced by weights 57 and are provided with a latch mechanism 58 to support the hooks 56 in a position clear of the bed 1 when the gripper head 4 is travelling.

The hooks 56 provide the anchorage by engaging in machined slots 59 in the fabricated bed 1 and these are arranged to give a slight undercut as indicated at 60. The surfaces engaging with the hooks 56 may be formed by placing two plates one above the other with their top faces together, the engaging surfaces being turned by means of a boring machine or other suitable tool. If necessary a distance piece may be placed between the plates in order to obtain the requisite amount of undercut.

For moving the travelling gripper head 4 there is employed a winch 61 driven by an electric motor 62 operating through a worm reduction gear, and a chain drive on to a back shaft. On this back shaft may be arranged two chain sprockets or rope drums carrying chains or ropes 63 attached to the travelling head 4 and then passing around return pulleys.

In order to avoid the possibility of mechanical damage due to the strap sagging between the travelling gripper head 4 and the uncoiler-leveller-recoiler 2 a number of swinging supporting arms 64 are provided. These arms 64 are provided with rollers 65 to be engaged by a cam plate 66 on the head 4 and to vertical shafts 67 to which the arms 64 are attached, are also affixed arms 68 to which is anchored one end of springs 69 fixed at the other end, these springs operating as over-centre springs.

As the gripper head 4 travels along the bed 1

away from the uncoiler-leveller-recoiler 2 the cam 66 engages the various rollers 65 the cam 66 effecting part of the movement of the arms and the movement being completed by the over-centre springs 69 which swing the various supporting arms 64 across the bed beneath the strip to the position shown in Figure 7 this position being determined by stops 70. The arms 64 are so arranged that on the return movement of the gripper head 4 they are pushed clear of the head this being effected by a roller 71 on the head 4 engaging the arms 64 and the final position being determined by stops 72. The tops of the supporting arms 64 may be faced with anti-scratching material and/or rollers as shown at 73.

In operation, in the case of heavy strip, the coil is placed on the carrier rolls 1 of the uncoiler-leveller-recoiler 2. The tail end of the strip is fed between the upper and lower banks A, B of the levelling rolls 8 which have been previously lowered under the action of the hydraulically or pneumatically operated wedges 18 working against the counterbalancing springs 17. The relative setting of the rolls will have been predetermined according to the gauge of material being operated upon.

The driving motor 9 is then started and is run until sufficient material has been delivered to pass through the levelling rolls 8 into the travelling gripper head 4 which will have been brought to its nearest position by means of the winch 61. The material is then gripped in the head 4 and thereupon the winch 61 and the drive of the uncoiler-leveller-recoiler are operated so that they run together until such time as the other end of the strip is approaching the levelling rolls 8.

The uncoiler-leveller-recoiler and the winch are then set in motion in the forward direction for a short period until this end of the strip has passed almost through the levelling rolls, when it will have been flattened. At this stage both the uncoiler-leveller-recoiler and the winch are reversed in motion so as to feed the flattened end of material into the gripper jaws of the other head 5. The material will then be gripped and the bearing blocks 15 are raised by withdrawing the wedge operating devices 18 to raise the levelling rolls 8 of the upper bank A and the carrier rolls 1. Then the top of the bottom rolls will be clear of the strip.

Whilst this is being carried out another operator will be releasing the latch mechanism 58 to release the anchorage hooks 56 so that they drop into the nearest notches 59 in the bed 1. Hydraulic pressure will then be admitted to the cylinder 6 forcing the main ram 49 to pull the other gripper head 5 away from the travelling head 4. The hydraulic ram 6 has sufficient stroke to enable the hooks 56 of gripper head 4 to be brought into engagement with the nearest locating notch 59 and also to stretch the strip to effect the flattening required. When the hooks 56 have engaged with the surface of the notches 59 the head 4 will become stationary and the stretching will take place and when the operator has judged that the strip has been properly flattened, he will then remove the hydraulic pressure, lower the blocks 15 carrying the upper bank of levelling rolls 8 and then will release the grip in the head 5. At the same time the other operator will raise the anchoring hooks 56 out of the notches in the bed and will latch them up by the mechanism 58.

The winch and the uncoiler-leveller-recoiler are then again started up so as to withdraw the

strip from the head 5 and bring the end portion into the levelling rolls. The operation is stopped when material has passed the adjustable bending roll 8' and this roll is then raised to a predetermined position to give the desired diameter of coil and the motors 9 and 62 are started up so as to re-form the coil. As the travelling gripper head 4 approaches the end of its travel the machine will be stopped, the grip released and the coil finally formed. This coil will be lifted away and a further coil placed in position.

In the case of light gauge material this will be mounted on the drum type uncoiler-coiler 3. The drum will be expanded and the material fed by hand into the levelling rolls 8 when the cycle will be exactly similar to that described above. On completion of the stretching operation it will not be necessary to bend the material by means of the bending roll 8', but after release from the grippers in the gripper head 5 the material may be engaged in the driving slot of the drum so as to enable the coil to be re-formed.

The machine might be designed so as to allow the travelling gripper head 4 to be pulled back by means of the uncoiler-leveller-recoiler, but it is considered preferable to have a positive drive for causing the gripper head 4 to travel in each direction since with thin gauge material resistance to motion of the travelling gripper head and its attendant parts may be sufficient to over-stretch the material. In any case it is desirable that some form of slipping clutch be provided in the drive of the winch 61 so as to compensate for any slight speed variation.

Various alternative methods may be employed for moving the travelling gripper head 4. For instance the head may be attached to a heavy link chain or chains of sufficient strength to withstand the stretching load. This would require to be provided with a heavy nonreversing drive also to withstand the load, although the motor operating this need not necessarily be of high power.

With this arrangement the provision of notches 59 in the bed would be avoided, but the overall expense would be considerably greater particularly when dealing with long lengths of strip, that is of the order of 100 feet to 150 feet.

It will be understood of course that many other modifications in the design and construction of the machine may be made within the scope of the invention.

What I claim is:

1. In a machine for uncoiling, leveling, stretching and recoiling metal strip, means for supporting a coil of the strip for rotation; a leveling device comprising spaced pressure exerting roll means between which said strip is adapted to pass longitudinally; means mounting the pressure exerting roll means on one side of said strip for movement selectively towards and from the pressure exerting roll means on the other side of said strip for respectively applying leveling pressure on said strip and for discontinuing the application of leveling pressure and thereby leaving said strip free to extend between the pressure applying roll means on opposite sides of the strip unrestrained by said pressure exerting roll means against longitudinal movement; a first gripper head; a second gripper head; means mounting said gripper heads respectively on opposite sides of said leveling device in the direction in which said strip passes through said leveling device; means for driving said pressure exerting roll means to unwind the strip from said coil and forward it to said first gripper head; means on

said first gripper head for gripping the extended end of the thus forwarded strip; means for moving said first gripping head away from said leveling device while the strip is being moved between said pressure exerting roll means until said strip has been uncoiled and the opposite end portion of the strip has been leveled; means for reversing the drive to said pressure exerting roll means for moving said strip reversely and toward said second gripper head accompanied by reverse movement of said first gripper head with the gripping means thereon still gripping said strip extended end; means on said second gripping head for gripping said opposite end of said strip; means for moving said movably mounted pressure exerting roll means away from the pressure exerting roll means on the other side of said strip to leave the strip free from restraint against longitudinal movement by said roll means; means for effecting relative separating movement of said gripper heads to stretch said strip; and means for deflecting said strip to coil it upon being again fed through said leveling device after at least one end of the strip has been released from the associated gripper head.

2. In a machine for uncoiling, leveling, stretching and recoiling metal strip, means for supporting a coil of the strip for rotation; a leveling device comprising spaced pressure exerting roll means between which said strip is adapted to pass longitudinally; means mounting the pressure exerting roll means on one side of said strip for movement selectively towards and from the pressure exerting roll means on the other side of said strip for respectively applying leveling pressure on said strip and for discontinuing the application of leveling pressure and thereby leaving said strip free to extend between the pressure applying roll means on opposite sides of the strip unrestrained by said pressure exerting roll means against longitudinal movement; a first gripper head; a second gripper head; means mounting said gripper heads respectively on opposite sides of said leveling device in the direction in which said strip passes through said leveling device; means for driving said pressure exerting roll means to unwind the strip from said coil and forward it to said first gripper head; means on said first gripper head for gripping the extended end of the thus forwarded strip; means for moving said first gripping head away from said leveling device while the strip is being moved between said pressure exerting roll means until said strip has been uncoiled and the opposite end portion of the strip has been leveled; means for reversing the drive to said pressure exerting roll means for moving said strip reversely and toward said second gripper head accompanied by reverse movement of said first gripper head with the gripping means thereon still gripping said strip extended end; means on said second gripping head for gripping said opposite end of said strip; means for moving said movably mounted pressure exerting roll means away from the pressure exerting roll means on the other side of said strip to leave the strip free from restraint against longitudinal movement by said roll means; means for effecting relative separating movement of said gripper heads to stretch said strip; and means for recoiling said strip upon its being again fed through said leveling device after at least one end of the strip has been released from the associated gripper head.

3. In a machine for uncoiling, leveling, stretching and recoiling metal strip, means for support-

ing a coil of the strip for rotation; a leveling device comprising spaced pressure exerting roll means between which said strip is adapted to pass longitudinally; means mounting the pressure exerting roll means on one side of said strip for movement selectively towards and from the pressure exerting roll means on the other side of said strip for respectively applying leveling pressure on said strip and for discontinuing the application of leveling pressure and thereby leaving said strip free to extend between the pressure applying roll means on opposite sides of the strip unrestrained by said pressure exerting roll means against longitudinal movement; a first gripper head; a second gripper head; means mounting said gripper heads respectively on opposite sides of said leveling device in the direction in which said strip passes through said leveling device; means for driving said pressure exerting roll means to unwind the strip from said coil and forward it to said first gripper head; means on said first gripper head for gripping the extended end of the thus forwarded strip; means for moving said first gripping head away from said leveling device while the strip is being moved between said pressure exerting roll means until said strip has been uncoiled and the opposite end portion of the strip has been leveled; an arm for supporting said strip; means mounting said arm for movement into and out of the path of said first gripper head and into and out of supporting position with respect to said strip; means responsive to movement of said first gripper head during uncoiling of said strip for moving said arm into strip supporting position between said first gripper head and said leveling device; means for reversing the drive to said pressure exerting roll means for moving said strip reversely and toward said second gripper head accompanied by reverse movement of said first gripper head with the gripping means thereon still gripping said strip extended end; means responsive to reverse movement of said first gripper head for moving said arm out of said strip supporting position; means on said second gripping head for gripping said opposite end of said strip; means for moving said movably mounted pressure exerting roll means away from the pressure exerting roll means on the other side of said strip to leave the strip free from restraint against longitudinal movement by said roll means; means for effecting relative separating movement of said gripper heads to stretch said strip; and means for recoiling said strip upon its being again fed through said leveling device after at least one end of the strip has been released from the associated gripper head.

4. In a machine for uncoiling, leveling, stretching and recoiling metal strip, means for supporting a coil of the strip for rotation; first and second gripper heads mounted for movement in line with each other, and being adapted to grip opposite ends of a strip extending between said heads; a leveling device comprising roll means mutually opposed to engage opposite sides of the strip extending between said heads; the roll means on one side of the strip being positioned to leave the strip free to extend in a straight line between said heads and the roll means on the other side of the strip being mounted for movement towards and from the strip for respectively engaging and being disengaged from said strip; means for driving said roll means forwardly to unwind the strip from the coil and forward it to said first gripper head; means for moving said first gripping head away from said leveling de-

vice while said strip is being thus moved and until said strip has been uncoiled and the opposite end portion of said strip has been leveled; means for reversing the drive to said roll means for moving said strip reversely toward said second gripper head accompanied by reverse movement of said first gripper head and movement of said strip opposite end into engagement with said second gripper head; means for moving said movably mounted roll means away from the strip; means for effecting relative separation of said gripper heads to stretch said strip; and means for recoiling said strip upon its being again fed through said leveling device after at least one end of the strip has been released from the associated gripper head.

5. The method of uncoiling, stretching and recoiling a strip in one machine having coiling and uncoiling means and banks of leveling rolls, comprising uncoiling a coil of the strip positioned on said means by rolling passage through the banks in one direction, passing said strip partially through said banks in the opposite direction until the opposite ends of the strip are disposed respectively on opposite sides of said banks, moving one bank away from the other to relieve the strip of rolling pressure, gripping the strip on opposite sides of said banks while the strip extends through said banks, thereupon stretching the strip, releasing the gripping of said strip, 10 moving said one bank toward the other to bring said leveling rolls into feeding engagement with said strip, adjusting the position of one roll of one bank relatively to the remainder thereof, and in returning said strip through the banks in feeding engagement therewith and recoiling it on said means through the position and action of said one roll.

10. The method of uncoiling, stretching and recoiling a strip in one machine having coiling and uncoiling means and banks of leveling rolls, comprising uncoiling a coil of the strip positioned on said means by rolling passage through the banks in one direction, passing said strip partially through said banks in the opposite direction until the opposite ends of the strip are disposed respectively on opposite sides of said banks, moving one bank away from the other to relieve the strip of rolling pressure, gripping the strip on opposite sides of said banks while the strip extends through said banks, thereupon stretching the strip, releasing the gripping of said strip, 15 moving said one bank toward the other to bring said leveling rolls into feeding engagement with said strip, driving said leveling rolls to feed said strip, and recoiling the strip as it is fed through said leveling rolls.

NORMAN CECIL LAKE.
